CLAIM

The ornamental design for a lamp shade, as shown and described.

DESCRIPTION

FIG. 1 is a front perspective view of a lamp shade in accordance with the invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

That which is depicted in solid lines in the drawing represents the claimed invention and that which is depicted in broken lines in the drawing forms no part of the claimed invention.
